COLLAPSIBLE BOX

Murray Kretchmer, New York, N. Y.

Application September 14, 1939, Serial No. 294,845

7 Claims. (Cl. 229—36)

This invention relates to collapsible boxes.

An object of this invention is to provide a box of the character described, which may be made of a single blank of corrugated cardboard, cardboard, fiberboard, paper, or the like sheet material, having triple thickness at the sides and double thickness at the ends, whereby to strengthen and rigidify the box, and to permit stacking of filled boxes without collapsing of the boxes, the construction being such that no strings or staples are necessary to retain the boxes in set up position.

A further object of this invention is to provide a box of the character described, having a pair of top covers, provided with handles, and means to lock the handles together for drawing the top covers together and preventing opening of the covers, whereby the handles rigidify the box, said handles furthermore being in face to face relation, thereby producing a handle of double thickness, the handles furthermore being relatively wide at the point of junction of the handles to the cover to prevent the handles from tearing away, the interlocking means furthermore serving to cover the crack between the handles and sealing the cover.

Yet another object of this invention is to provide in a box of the character described, a pair of overlapping cover members extending from opposite sides toward each other, one of the covers being provided with hooks to engage within slits in the other cover to hold the cover against opening up and to strengthen the box.

A still further object of this invention is to provide a box of the character described, having a pair of top covers provided with mutually contacting handles, said handles being adapted to be flattened down against one of the covers to permit the boxes to be stacked.

Still a further object of this invention is to provide in a box of the character described, a bottom wall and side walls and flaps extending from the ends of the side walls and adapted to interlock, and end walls extending from the bottom wall adapted to be folded upwardly against the interlocked flaps and carrying cover sections adapted to overlap at the top of the box, and the cover sections being provided with flaps adapted to engage the side walls of the box.

A still further object of this invention is to provide a relatively strong and durable collapsible box of the character described, which shall be relatively inexpensive to manufacture, which shall necessitate a minimum of sheet material, which shall be easy to set up and collapse,

which may be made of lighter paper or cardboard because of its rigidity, and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

15 Fig. 1 is a perspective view of a collapsible box embodying the invention;

Fig. 2 is a cross-sectional view taken on line 2—2 of Fig. 1;

Fig. 3 is a cross-sectional view taken on line 20 3—3 of Fig. 1;

Fig. 4 is a top plan view of a blank from which the improved box is made;

Fig. 5 is a perspective view showing the box partly set up;

25 Fig. 5a is a partial view of Fig. 5, but illustrating a modified construction;

Fig. 5b is a view similar to Fig. 5a, and illustrating a still further modified construction;

Fig. 6 is a perspective view of a box embodying 30 the invention, and illustrating a modified construction;

Fig. 7 is a cross-sectional view taken on line 7—7 of Fig. 6;

Fig. 8 is a top plan view of the blank from 35 which the box shown in Fig. 6 is made;

Fig. 9 is a perspective view of the box shown in Fig. 6, partly set up;

Fig. 10 is a perspective view of a box embodying the invention, and illustrating a still further modified construction;

Fig. 11 is a cross-sectional view taken on line 40 11—11 of Fig. 10;

Fig. 12 is a top view of the blank showing the box of Fig. 10; and

45 Fig. 13 is a perspective view of the box shown in Fig. 10, partially set up.

Referring now in detail to the drawings, 50 Fig. 10 designates a box embodying the invention, made from a single blank 11 of paper cardboard, corrugated cardboard, fiberboard, or the like sheet material.

The blank 11 comprises a central section 12 constituting the bottom wall of the box. Extending from the sides of section 12 are similar sections 13, 13a adapted to be folded upwardly to

form the side walls of the box. Said sections 13 are formed with longitudinal slits 13b, for the purpose hereinafter appearing.

Extending from the ends of sections 12 are similar, symmetrical sections 14, 14a, adapted to be folded upwardly, as shown in Fig. 1 of the drawings, to form end walls for the box.

Extending from the ends of sections 13 are flaps 16 formed with slits 17; and extending from the ends of sections 13a are flaps 18 formed with hooks 19 adapted to be received within the slits 17 of flap 16. The flaps 16, 18 are the same height as side walls 13, 13a.

In setting up the box, the sections 13, 13a are first folded upwardly and then the flaps 16 and 18 are folded toward each other into alignment, and the hooks 19 engage slits 17. The interlocked flaps 16 and 18 thus maintain the walls 13, 13a in vertical position.

Extending from the outer ends of sections 13, 13a are narrow flaps 23 adapted to be folded downwardly into horizontal position to underlie cover flaps, to be described hereinafter.

Extending from the sections 14, 14a are overlapping sections 24, 24a adapted to be folded down over the top of the box and constituting cover sections for the box. Section 24 is formed with a trapezoidal hole or cut-out 25 parallel to the outer edge thereof. The opening or hole 25 has parallel edges 25a and 25b, parallel to the outer edge of section 24 and also outwardly inclined edges 25c at the ends of said hole. Section 24 is also formed with inwardly inclined edges 26 extending to the outer end of said section forming with the opening 25a, a handle member 27 which may be folded about crease lines 28, to upstanding position relative to section 24. Adjacent the edges 26 are hooks 30, for the purpose herein-after appearing.

Section 24a is formed with inwardly inclined slits 32, similar to the inclined edges 26. Said section 24a is also formed with a slit 33 registering with the edge 25a of the hole 25. Said section is also formed with outwardly inclined slits 34 registering with the inclined edges 25c of the hole 25. The slits 32, 33, 34 form a handle member 27a similar to the handle 27, adapted to be folded about crease lines 36 to an upstanding position relative to section 24a, into face to face contact with said handle 27.

The dove-tail portion 38 bounded by the slits 33, 34 forms an interlocking tab which passes through the dove-tail hole 25 to draw the cover members 24, 24a together, and to lock the handles 27, 27a into mutually contacting position. Section 24a is formed with a pair of inclined slits 40 adapted to receive the hooks 30 of section 24 for further locking the cover sections 24, 24a together.

As shown in the drawings, the cover sections 24, 24a overlap, and the handles 27, 27a are positioned on the longitudinal mid portion of the box, so that said handles will come into face to face relation when the box is set up.

Extending from the ends of sections 24, 24a are flaps 43 provided with hooks 44 adapted to engage in the slits 13b. The hooks 44 are located adjacent the outer ends of the flaps 43, and are of such width as to contact the bottom of the box. Thus the flaps 43 on each side of the box overlap, and the hooks 44 thereof pass through the single slit 13b.

It will now be understood that the box has triple thickness at the sides and double thickness at the ends to produce a strong and rigid box.

The handles 27 may be folded down against the top of the box when stacking the boxes. By folding up one pair of sections 13, 13a, interlocking one pair of flaps 16, 18 and folding one end of the box upwardly, and engaging one set of flaps 43 in the slits 13b, the opposite end of the box will be open, so that articles may be shoved into the box. Thereafter, the other pair of flaps 16, 18 may be interlocked and the other cover folded into position to complete closure of the box.

The hooks 30 engaging in the slits 40 serve to strengthen and rigidify the box, and are particularly useful for wide boxes.

It will be noted that no strings or staples are necessary to maintain the box in set up condition. The handles draw the top covers of the box together, thus preventing opening up of the box. The handles furthermore rigidify the box and are strong because they are double. The dove-tail tab or portion 38 interlocks the handles, draws the covers together, and covers up the crack between the handles to seal the box.

If desired, the outer edges 26, 32 of the handles 27, 27a may be parallel instead of inclined. It will be noted that the base of the handles are relatively wide, thus producing strong handles. Since the box is strong and rigid, it may be made of thinner cardboard. The invention disclosed herein may be embodied in egg boxes, cake boxes, or boxes for any other suitable purposes.

In Fig. 5a there is shown a box 10a, similar to box 10, with the exception that the hooks 44a on flaps 43 are at the inner ends of the flaps, instead of at the outer ends of the flaps.

In Fig. 5b there is shown a box 10b, similar to box 10, with the exception that on each flap 43 are a pair of hooks 44b engaged within a pair of slits 50 in the side sections 13, 13a and replacing the slits 13b.

In Figs. 6 to 9 there is shown a box 10c, similar to box 10a, with the exception that there is substituted for the interlocking flaps 16, 18 on said box 10a, flaps 53 extending from the ends of each of sections 14, 14a having hooks 53a thereon engaging in slits 54 in sections 13, 13a. When the box is set up, the hooks 53a are engaged in the slits 54 to maintain the sections 13, 13a, 14, 14a in vertical upstanding position.

In Figs. 10, 11, 12 and 13 there is shown a box 10d, embodying the invention, similar to box 10a, with the exception that in box 10d the sections 13 and 13a are attached to sections 14, 14a by means of triangular corner tabs 55 at the ends of sections 14, 14a pasted to the insides of the ends of sections 13, 13a.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A box comprising a bottom section, side sections extending upwardly from the sides of the bottom section, and formed with slits, end sections extending upwardly from the ends of said bottom section, cover sections extending from the end sections, said cover sections being pro-

vided with mutually contacting, upstanding handles, and flaps at the ends of said cover sections having portions engaging in the slits of the side sections, one of said handles being formed with a finger opening, the other of said handles being formed with a finger opening registering with the first opening, one cover section having a tab projecting through the opening in the handle carried by the second cover section and overlying said second cover section, said tab having means to engage edge portions of the handle carried by the second cover section at the ends of the opening therein, to interlock the handles together, said second cover section having portions overlying the first cover section and engaging end edges of the handle carried by the first cover section to interlock said handles, and said first cover section being formed with slits, and said second cover section being formed with portions engaging within said slits.

2. A box comprising a bottom section, side sections extending upwardly from the sides of the bottom section, and formed with slits, end sections extending upwardly from the ends of said bottom section, a pair of flaps extending from the ends of each side section and contacting the inner surfaces of said end sections, at least one flap on one side section having means to interlock with one flap on the other side section, cover sections extending from the end sections, said cover sections being provided with mutually contacting, upstanding handles, and flaps at the ends of said cover sections having portions engaging in the slits of the side sections, one of said handles being formed with a finger opening, the other of said handles being formed with a finger opening registering with the first opening, one cover section having a tab projecting through the opening in the handle carried by the second cover section and overlying said second cover section, said tab having means to engage edge portions of the handle carried by the second cover section at the ends of the opening therein, to interlock the handles together, said second cover section having portions overlying the first cover section and engaging end edges of the handle carried by the first cover section to interlock said handles, and said first cover section being formed with slits, and said second cover section being formed with portions engaging within said slits.

3. A box comprising a bottom section, side sections extending upwardly from the sides of the bottom section, and formed with slits, end sections extending upwardly from the ends of said bottom section, cover sections extending from the end sections, said cover sections being provided with mutually contacting, upstanding handles, and flaps at the ends of said cover sections having portions engaging in the slits of the side sections, one of said handles being formed with a finger opening, the other of said handles being formed with a finger opening registering with the first opening, one cover section having a tab projecting through the opening in the handle carried by the second cover section and overlying said second cover section, said tab having means to engage edge portions of the handle carried by the second cover section at the ends of the opening therein, to interlock the handles together, said second cover section having portions overlying the first cover section and engaging end edges of the handle carried by the first cover section to interlock said handles, and said first cover section being formed with slits,

and said second cover section being formed with portions engaging within said slits, the flaps on one cover section overlapping the flaps on the other cover section.

- 5 4. A box comprising a bottom section, side sec-
tions extending upwardly from the sides of the
bottom section, and formed with slits, end sec-
tions extending upwardly from the ends of said
bottom section, cover sections extending from
10 the end sections, said cover sections being pro-
vided with mutually contacting, upstanding han-
dles, and flaps at the ends of said cover sections
15 having portions engaging in the slits of the side
sections, one of said handles being formed with
20 a finger opening, the other of said handles being
formed with a finger opening registering with
the first opening, one cover section having a tab
25 projecting through the opening in the handle
carried by the second cover section and overlying
said second cover section, said tab having means
30 to engage edge portions of the handle carried
by the second cover section at the ends of the
opening therein, to interlock the handles to-
gether, said second cover section having portions
35 overlying the first cover section and engaging end
edges of the handle carried by the first cover
40 section to interlock said handles, and said first
cover section being formed with slits, and said
second cover section being formed with portions
45 engaging within said slits, the flaps on one cover
section overlapping the flaps on the other cover
50 section, said flaps on the cover sections extending
down to the bottom section.

5 5. A box comprising a bottom section, side sec-
tions extending upwardly from the sides of the
bottom section, and formed with slits, end sec-
tions extending upwardly from the ends of said
55 bottom section, cover sections extending from the
end sections, cover sections being provided with
60 mutually contacting, upstanding handles, and
flaps at the ends of said cover sections having
65 portions engaging in the slits of the side sections,
one of said handles being formed with a finger
70 opening, the other of said handles being formed
75 with a finger opening registering with

the first opening, one cover section having a tab projecting through the opening in the handle carried by the second cover section and overlying said second cover section, said tab having means to engage edge portions of the handle carried by the second cover section at the ends of the opening therein, to interlock the handles together, said second cover section having portions overlying the first cover section and engaging end edges of the handle carried by the first cover section to interlock said handles, and said first cover section being formed with slits, and said second cover section being formed with portions engaging within said slits, the flaps on one cover section overlapping the flaps on the other cover section, the slit engaging portions of the flaps which extend from each cover section being located between the handles and the end sections from which the other section extends.

7. A box comprising a bottom section, side sections extending upwardly from the sides of the bottom section, and formed with slits, end sections extending upwardly from the ends of said bottom section, cover sections extending from the end sections, said cover sections being provided with mutually contacting, upstanding han-

5 dles, and flaps at the ends of said cover sections having portions engaging in the slits of the side sections, one of said handles being formed with a finger opening, the other of said handles being formed with a finger opening registering with the first opening, one cover section having a tab projecting through the opening in the handle carried by the second cover section and overlying said second cover section, said tab having means to engage edge portions of the handle carried by the second cover section at the ends of the opening therein, to interlock the handles together, said second cover section having portions overlying the first cover section and engaging end edges of the handle carried by the first cover section to interlock said handles, and said first cover section being formed with slits, and said second cover section being formed with portions engaging within said slits, and flaps extending 10 from the ends of said side section and contacting the inner surfaces of the end sections, the flaps on one side section having means to interlock the flaps on the other side section.

25

MURRAY KRETCHMER.
